CLAIM

The ornamental design for a scope mount, as shown and described.

DESCRIPTION

FIG. 1 is a top, front, right side perspective view of a scope mount showing my new design;

FIG. 2 is a bottom, rear, left side perspective view thereof;

FIG. 3 is a right side elevational view thereof;

FIG. 4 is a left side elevational view thereof;

FIG. 5 is a top plan view thereof;

FIG. 6 is a bottom plan view thereof; and,

FIG. 7 is a front elevational view thereof, the rear elevational view being a mirror image thereof.

1 Claim, 7 Drawing Sheets(56)
